WINDOW VENTILATOR

John C. Gerken, Detroit, Mich.

Application February 8, 1945, Serial No. 576,810

2 Claims. (Cl. 98—99.8)

1

My invention relates to a new and useful improvement in a window ventilator adapted for mounting below a raised sash of the window and has for its object the provision of a ventilator of this class which will be light, durable, compact, of simple construction, economical of manufacture and highly efficient in use.

Another object of the invention is the provision of a window ventilator of this class which may be mounted in windows of various sizes, the ventilator being self-adjusting transversely.

Another object of the invention is the provision of a window ventilator of this class so constructed and arranged that a screen frame embodying a screen may be easily and quickly placed in position in the ventilator.

Other objects will appear hereinafter.

It is recognized that various changes and modifications may be made in the detail of structure illustrated without departing from the invention itself and it is intended that such variations and modifications shall be encompassed within the scope of the claims which form a part hereof.

Forming a part of this specification are drawings in which,

Fig. 1 is a front elevational view of the invention;

Fig. 2 is a rear elevational view of the invention;

Fig. 3 is a sectional view, slightly enlarged, taken on line 3—3 of Fig. 1;

Fig. 4 is a sectional view taken on line 4—4 of Fig. 3, with a part broken away;

Fig. 5 is a fragmentary, slightly enlarged, sectional view taken on line 5—5 of Fig. 4;

Fig. 6 is a fragmentary, slightly enlarged view taken on line 6—6 of Fig. 2;

Fig. 7 is a fragmentary elevational view taken on line 7—7 of Fig. 6;

Fig. 8 is a slightly enlarged, fragmentary sectional view.

The structure comprises a frame embodying a side rail 15, which is preferably formed tubular and from sheet metal, having the groove 16 formed in the outer face 17 thereof. A channel-shaped side rail embodying the legs 18 and 19 and the bight 20 is positioned opposite the side rail 15. It is preferred to form the entire structure out of sheet metal for the purposes of durability and lightness. These side rails are connected together at their tops by the top rail 21 having at its outer edge the downwardly turned flange 22 and an upwardly turned flange 23 at its forward end. The side rails are connected at their lower ends by the bottom rail 25 having the downwardly offset portion 25 which is

provided with the angularly turned portion 26. In use, the window sash would be raised and the frame described inserted beneath the window within the window frame. The bottom rail 24 would lie upon the window sill and the top rail would be engaged by the bottom rail of the window sash. The side rail 15 is provided with a liner 27 which extends inwardly beyond the inner face of the rail 15. A similar plate 28 of sheet metal is secured to the inner face of the bight 20. The plate 27 is doubled upon itself at its inner edge as at 29 to provide a channel 30. The plate 20 is doubled upon itself as at 31 to provide a channel 32. I provide a screen embodying the top rail 33, the bottom rail 34, the side rail 35 and the side rail 36, which serve as a support for the screen wire 37. As clearly shown in Fig. 4, this screen frame is so constructed that the screen wire 37 is bound in the rails by doubling the rails upon themselves. The screen frame is slid into the channels 30 and 32. The screen frame is slid into the channels 30 and 32 from above and the upper rail 33 is provided with the downwardly bent flange 38 which seats over the upwardly turned portion 23 of the rail 24. The lower rail 34 of the screen frame is doubled upon itself as at 39 to provide a channel in which the upwardly turned flange 40 on the rail 24 engages so that a very close connection is thus provided and one which is closely enough sealed for the purposes intended so that flies, mosquitoes and so forth cannot enter.

Extending between and connecting the plates 27 and 28 are louvers 41, these louvers engaging at their opposite ends the plates 27 and 28 and being welded, soldered or otherwise secured thereto. As shown in Fig. 3, the louvers are inclined downwardly and outwardly so that an effective watershed is thus provided. A tubular rail 42 is mounted in the channel formed by the legs 18 and 19 of the side rail. This rail 42 is provided in its outer face with the groove 43 in which the window stop or window strip may engage. This rail 42 also carries a bolt 44 which is projected through the bight 20 and the plate 28 so that the rail 42 may be pushed inwardly toward the bight 20 against the compression of the spring 45.

A channel-shaped adjusting rail 46 is adapted for mounting on the rail 15, this adjusting rail being provided with the groove 47 on its face 48 for reception of the weather strip or a window stop. It is intended that these adjusting rails 46 be made of different widths so that the structure may thus quickly be modified as to its width to fit windows of various widths. When the

proper size rail 46 has been mounted in position and it is intended to mount the structure in a window opening, the end bearing the rail 46 would first be inserted in the window opening so that the weather strip or guide strip would engage in the channel or groove 47. The structure may then be swung until the rail 42 engages the window frame, whereupon the rail 42 would be pressed inwardly against the compression of the spring 45 until the entire structure had moved into position. In this way, an easy and quick mounting of the structure in the window opening is provided and one which will prevent rattling.

The method of securing the rail 46 on the rail 15 is a simple and effective one. The rail 15 carries studs 49 on which are heads 50. The sides of the adjusting rail 46 are provided with bayonet slots 51 spaced apart to receive the studs 49. With this type of structure, the adjusting rail may be easily mounted in position and, when moved longitudinally, secured against undue removal.

The rail 42 may be locked against inward movement after it has been mounted in position. This rail carries the slidable plate 52 projecting outwardly from which is a stud 53 engaging in the cut away portion 54 of the leg 18. When the plate is swung to position, where the stud 53 will register with the slot 55 formed in the plate 18, the rail 42 may be pressed inwardly, the stud travelling inwardly of the slot 54. When in the position shown in Fig. 7, the inward movement of the rail 42 is prevented through the engagement of the stud 53 with the edge of the cut away portion of the rail 18.

Experience has shown that a construction of this type is one which is most effective in use and which is light and may be easily handled so that it may be placed in position and be moved by a woman, while, at the same time, the structure is one which is of such durability that it cannot be easily damaged.

What I claim as new is:

1. A ventilator of the class described comprising a frame embodying a pair of oppositely disposed side rails and a top rail and bottom rail all rigidly connected together; an angularly turned portion on one of the corresponding edges of the said side rails to provide an outwardly projecting shoulder and an inwardly faced channel on said edge of each of said side rails; a U-shaped member mounted on and engaging at its bight with the outer face of one of said side rails, and engaging at the outer face of one of its legs with the inner face of the shoulder on said side rails; a tubular member slidably mounted between the legs of said U-shaped member and movable inwardly and outwardly thereof; a spring for normally resisting inward movement of said tubular member relatively to said U-shaped member; a tubular member rectangular in cross-section and engaging at one of its sides with the outer face of the other of said side rails and secured there-

to, the outer face of one of the sides of said tubular member engaging the inner face of the shoulder of said side rail; and a U-shaped extension mounted on and projecting outwardly from said tubular member.

2. A ventilator of the class described comprising a frame embodying a pair of oppositely disposed side rails and a top rail and bottom rail all rigidly connected together; an angularly turned portion on one of the corresponding edges of the said side rails to provide an outwardly projecting shoulder and inwardly faced channel on said edge of each of said side rails; a U-shaped member mounted on and engaging at its bight with the outer face of one of said side rails, and engaging at the outer face of one of its legs with the inner face of the shoulder on said side rail, a tubular member slidably mounted between the legs of said U-shaped member and movably inwardly and outwardly thereof; a spring for normally resisting inward movement of said tubular member relatively to said U-shaped member; a tubular member rectangular in cross-section and engaging at one of its sides with the outer face of the other of said side rails and secured thereto, the outer face of one of the sides of said tubular member engaging the inner face of the shoulder of said side rail; and a U-shaped extension mounted on and projecting outwardly from said tubular member; a plate slidably mounted on said first named tubular member; a projection extending outwardly from said plate, there being a recess formed in one of the legs of said U-shaped member for accommodating said projection, said leg having, adjacent one end of said recess, an inwardly projecting notch formed therein for reception of said projection, said projection being movable into and out of registration with said notch, said projection, upon movement out of registration with said notch, preventing inward movement of said first named tubular member relatively to said U-shaped member.
